FEED-WATER CONNECTION TO BOILER
DRUM

Ward S. Patterson, Chappaqua, and Julian L. Barnes, Yonkers, N. Y., assignors to Combustion Engineering Company, Inc., New York, N. Y.

Application May 8, 1943, Serial No. 486,124

8 Claims. (Cl. 122—365)

This invention relates to tubular connections to fluid containing vessels and particularly to improvements in tubular connections through which a cold fluid flows into a vessel containing a relatively hotter fluid, such as the connection for introducing feed water into the drum containing saturated steam and water in a steam boiler.

It is recognized that where a tube enters a drum carrying fluid at a different temperature than that within the drum, special means should be provided to prevent the direct contact of the tube with the drum shell at its place of entry. For example, where a tube carrying cold liquid is rolled directly into a tube hole in a drum containing hot liquid the tube temperature would approach that of the fluid flowing therethrough while the temperature of the drum at the joint tends to approach that of the hotter fluid within. The resulting differences in expansion may cause the joint to leak. With great changes in temperature injurious internal stresses may occur within the drum metal near the joint. For this reason it has also been found desirable to avoid permitting a mass of fluid of a different temperature than that of the drum to directly contact the drum in a locally restricted area.

An object of this invention is to provide an improved connection between a tube and a vessel each of which is subject to different temperatures, whereby the metal at the joint is maintained at a substantially uniform temperature which is substantially equal to that of the vessel by being contacted by a current of fluid of uniform and proper temperature.

In the accompanying drawings:

Figures 1, 2, 3, 3a, 4 and 5 are vertical sectional views through the steam and water drum of a steam boiler, taken on the center line of a tube connection, and represent different forms of the invention.

Referring first to Figure 1, the steam and water drum 1 of a boiler is provided with a feed water pipe 2 passing freely into the drum through a surrounding tube 3 fastened to the drum as by rolling or welding into tube hole 4. Tubes 2 and 3 are preferably fastened together by sealing means 5 at a location outside of and spaced from the drum. In Figure 2 a third tube 6 spaced from tube 3 and fitting closely about pipe 2 is connected thereto at its inner end at a point 6a within the drum 1. The outer ends of tubes 3 and 6 are fastened and sealed at 6b. In both forms the feed water pipe 2 is surrounded by an annular space 7 between it and the tube that is fastened to the drum 1.

In Figure 1 a connection 9 is made near the outer end of the annular space between tubes 2 and 3 for introducing the steam and water mixture discharging from one or more risers 8 of a steam generating boiler. The temperature of the steam-water mixture entering through connection 9 is substantially equal to that of the steam and water within the drum 1 so that the water flowing through the annular space 7 between tubes 2 and 3 maintains the joint 4 between tube 3 and the drum shell 1 at substantially the temperature of the steam and water within the drum, thereby avoiding the difficulties produced by expansion and temperature stresses.

In Figure 3a the fragmentary longitudinal section shows a multiplicity of feed water connections 2, 3 like the one shown in Figure 3 in transverse section; these are arranged in alignment longitudinally of the drum. To provide a common connection for water at the temperature of the saturated steam within the drum a space or compartment 10 is formed longitudinally of the drum above a box 11 below the inner surface at the top of the shell 1, the space 10 being sealed from the interior of the drum along its longitudinal and end edges as at 12. One or more connections 9 discharge the steam and water mixture from the generating tubes 8 into the space or compartment 10 above box 11. From compartment 10 the water flows outwardly into the annular space 7 between tubes 3 and pipe 2 and thence inwardly through the open end of tube 13 and via the annular space between it and tube 2 discharging into the box 11 from which the water may be conducted to other apparatus within the drum, such as a steam and water separator or a steam purifier. In the absence of box 11 the water would discharge directly into drum 1 from tubes 13.

In Fig. 4 a compartment 10 similar to that of Fig. 3 is provided but located at the bottom of the drum beneath the water level. This compartment may cover a large sector at the bottom so as to protect the bottom locally against cooler feed water coming into contact with the drum shell and the tube joints. The water supply pipe 9 from the steam generating tubes may be provided with a restricted orifice 15 in order to limit the rate of flow, the purpose of which will be explained later. The water from compartment 10 flows downwardly through the annular space 7 around tube 13 and thence upwardly into the drum through the annular space 14 between tubes 13 and 2.

In Fig. 5 also the feed water connection is lo-

cated below the water line of the boiler and in this instance the boiler water of the drum is used to control the temperature of the metal at the joint 4 between drum shell 1 and tube 3. Feed water pipe extension 2A ends at a point within the limits of the concentric tube 13 and is formed into a nozzle 16 at its end. Tube 13 is shaped to form a Venturi throat 17 at a suitable distance downstream from nozzle 16. The boiler water flows downwardly through the annular space 6 between tubes 3 and 13 and thence upwardly through the latter at 7 around pipe 2 because of the ejector action of nozzle 16 and Venturi throat 17 and is mixed with the jet of water from nozzle 16 and discharged therewith through throat 17 and thence into the boiler drum.

The invention is particularly applicable to a forced circulation boiler in which parallel boiler tube circuits are each provided with restricted orifices, or resistances, for the purpose of insuring an adequate flow of water through each and all circuits. In Fig. 1 one of the boiler tube circuits 8 between the circulation pump discharge header and the steam and water drum is directed into the annular space between pipe 2 and tube 3. In Figs. 3 and 4 one or more of said circuits 8 are directed into the compartment 10. Should a directly connected tube be provided between the circulation pump and the compartment 10, a restricting orifice or a resistance 15, as shown in Fig. 4, may be introduced into the circuit so as to balance its resistance with that of the remaining boiler tube circuits which discharge directly into the steam and water drum.

What we claim is:

1. In a vessel containing a heated liquid having an outer tube fastened to the vessel and open at one end to the interior of the vessel, a tube for supplying a cold liquid to the vessel projecting through the outer tube and spaced from said outer tube to form an annular passage therebetween and means for fastening and sealing the inner to the outer tube at a point outside of and spaced from the vessel; and pump means for continuously supplying a positive current of liquid at a temperature substantially that of the liquid in the vessel to said annular passage.

2. In a vessel containing a heated liquid, an outer tube fastened to the vessel and open at one end to the interior of the vessel, a tube for supplying a cold liquid to the vessel projecting through the outer tube and spaced from said outer tube to form an annular passage therebetween and means for fastening and sealing the inner to the outer tube at a point outside of and spaced from the vessel; a third tube concentrically disposed intermediate the inner and outer tubes and spaced therefrom with one end open thereof adjacent the seal between said tubes and its other end extending into and open to the drum interior; and pump means for causing a continuous current of liquid of a temperature substantially equal to that of the liquid within said drum to flow positively through the annular passage between the outer and intermediate tubes and thence between the intermediate and inner tubes.

3. In a vessel containing a heated fluid having an outer tube fastened to the vessel and open at one end to the interior of the vessel, a tube for supplying a cold liquid to the vessel projecting through the outer tube and spaced from said outer tube to form an annular passage therebetween and means for fastening and sealing the inner to the outer tube at a point outside of and spaced from the vessel; a third tube concentri-

cally disposed intermediate the inner and outer tubes and spaced therefrom with one end open thereof adjacent the seal between said tubes and its other end extending into and open to the drum interior; and pump means for continuously causing a positive current of the liquid from within the drum to flow through the annular passage between the outer and intermediate tubes and thence between the intermediate and inner tubes.

4. In a vessel containing a heated liquid; an outer tube fastened to the vessel and open at one end to the interior of the vessel; partitions within the drum sealed to its walls to form a chamber closed off from the remainder of the vessel; a tube for supplying a cold liquid to the vessel projecting through said chamber and the outer tube to discharge into said vessel and spaced from said outer tube to form an annular passage therebetween; means for fastening and sealing the inner to the outer tube at a point outside of and spaced from the vessel; a third tube concentrically disposed intermediate the inner and outer tubes and spaced therefrom with one end open thereof adjacent the seal between said tubes and its other end extending through said chamber into and open to the drum interior; a liquid delivery tube connecting into said chamber; and pump means for continuously causing a positive current of liquid to flow into the chamber to pass thence sequentially through the annular passage between the outer and intermediate tubes and between the intermediate and inner tubes to the interior of the vessel.

5. In a vessel containing a heated fluid having an outer tube fastened to the vessel and open at one end to the interior of the vessel, a tube for supplying a cold fluid to the vessel projecting through the outer tube and spaced from said outer tube to form an annular passage therebetween and means for fastening and sealing the inner to the outer tube at a point outside of and spaced from the vessel; a third tube concentrically disposed intermediate the inner and outer tubes and spaced therefrom with one end open thereof adjacent the seal between said tubes and its other end extending into and open to the drum interior, a portion of said intermediate tube being formed into a Venturi throat; and a nozzle on the end of the inner positioned tube to discharge into the throat whereby a flow of fluid from the drum is induced to flow through the annular passage between the tubes by the jet of fluid from the nozzle.

6. In a vessel containing heated water; a tube connected to the vessel and open at one end to the interior of the vessel, a second tube for supplying cold water to the vessel projecting through the first tube and spaced therefrom to form an annular passage therebetween, and means for fastening and sealing the inner to the outer tube at a point outside of and spaced from the vessel; and a fluid circulating tube connected to discharge into the annular space between said concentric tubes adjacent the drum.

7. In a steam and water drum of a forced circulation boiler having a pump for circulating the water through steam generating tubes connected for discharge into the drum; a tube for supplying relatively cold water to the vessel projecting through the outer tube and spaced from said outer tube to form an annular passage therebetween; means for fastening and sealing the inner to the outer tube at a point outside of and spaced from the vessel; a tube connected at one end to the pump discharge and at the other end into the annular passage between the tubes adjacent

the drum for positively circulating hot water through said passage.

8. In a vessel containing a heated liquid; partition means extending transversely of the drum near its bottom sealed to its walls so as to form a chamber closed off from the remainder of the vessel at the bottom thereof; an outer tube connected to the vessel and open at one end to the interior of said chamber; a tube for supplying relatively cold liquid to the vessel projecting through said chamber and the outer tube to discharge into said vessel and spaced from said outer tube to form an annular passage therebetween below said partition; means for fastening and sealing the inner to the outer tube at a point outside of and spaced from the vessel; a third

15 tube concentrically disposed intermediate the inner and outer tubes and spaced therefrom with one end open thereof adjacent the seal between said tubes and its other end extending through said chamber into and open to the drum interior; a liquid delivery tube connecting into said chamber; and pump means for continuously causing a current of relatively hot liquid to flow positively into the chamber at the bottom of said vessel to pass thence sequentially through the annular passage between the outer and intermediate tubes and between the intermediate and inner tubes to the interior of the vessel.
